UNITED STATES PATENT OFFICE

135,455

DESIGN FOR A GAUGE FOR SIZE MEASUREMENT OR COMPARISON

Willis Fay Aller, Dayton, Ohio, assignor to The Sheffield Corporation, Dayton, Ohio, a corporation of Ohio

Application August 15, 1942, Serial No. 107,939

Term of patent 7 years

To all whom it may concern:

Be it known that I, Willis Fay Aller, a citizen of the United States of America, residing at Dayton, in the county of Montgomery, State of Ohio, have invented a new, original, and ornamental Design for a Gauge for Size Measurement or Comparison, of which the following is a specification, reference being had to the accompanying drawing, forming part thereof. In the drawing:

Fig. 1 is a front perspective view of a gauge for size measurement or comparison showing my new design;

Fig. 2 is a perspective view of the same as viewed from the front and side; and

Fig. 3 is a side elevational view thereof.

The broken line showings of parts in Fig. 2 have been omitted from Figs. 1 and 3 for convenience of illustration.

I claim:

The ornamental design for a gauge for size measurement or comparison, substantially as shown and described.

WILLIS FAY ALLER.
